United States Patent Office

Des. 229,880
Patented Jan. 15, 1974

229,880

POLE SEAT

Ernest A. Keith, Cleveland, Ohio, assignor to Corporation
(Ltd.), Cleveland, Ohio

Filed May 19, 1972, Ser. No. 255,317

Term of patent 14 years

Int. Cl. D6—01

U.S. Cl. D6—26

FIG. 1

FIG. 4

FIG. 2

FIG. 3

FIG. 1 is a side elevational view of a pole seat embodying my new design.

FIG. 2 is a front elevational view thereof.

FIG. 3 is a top plan view thereof.

FIG. 4 is a horizontal sectional view taken substantially along line 4-4 of FIG. 2.

I claim:

The ornamental design for a pole seat, as shown and described.
